PORTABLE DISPLAY BINDER

Arthur M. Barrett, Winnetka, Ill., assignor to The Barrett Bindery Co., Chicago, Ill., a corporation of Illinois

Application July 7, 1953, Serial No. 366,547

4 Claims. (Cl. 281—33)

The present invention relates to portable display devices and, particularly, to loose leaf binders of the easel type, adapted for use by salesmen and others in presenting to prospective customers sales literature, pictures, charts and analogous materials in convenient form.

Display devices of the general character are known, but prior proposals in the art have suffered certain disadvantages, among which are: lack of economy, impractical structural disposition of the components of the binder which leads to a lack of continuity in the presentation of material, inconvenient viewing angles, lack of adequate strength, lack of ready adaptability to revision of the material to be presented, and others.

It is an object of the present invention to provide an improved portable display binder overcoming the above noted disadvantages.

Another object of the invention is to provide an improved portable display binder adapted to assume and be used in three viewing positions, which positions provide optimum viewing angles for presentation of materials to a single person, or to groups of varying numbers of persons, whether those persons be sitting or standing, whereby the binder is adapted for a wide variety of sales and promotion presentations.

A further object of the invention is the provision of an improved display binder adapted for the accomplishment of the above objects and including full solid outside covers and backbone, whereby the binder is neat and attractive in appearance and of sturdy construction.

It is also an object of the present invention to provide an improved display binder including means for reinforcing and supporting the binding device incorporated in the binder, whereby the material to be presented is firmly supported, retained and guided in all positions which the binder is adapted to assume.

A still further object of the invention is the provision of reinforcing means for portions of the binder whereby the binder may be formed of light weight materials and yet be sturdy and provide a firm support for the materials to be presented.

In accordance with the above objects, and as additional objects of the invention, I provide an improved portable display binder comprising an outer case of substantially conventional loose leaf type binder construction including solid front and rear cover boards hingedly connected at their inner longitudinal edges to a solid backbone. This outer case is adapted for the reception of an inner case of generally similar construction and of substantially the same size, the two cases being hingedly connected along the top edges thereof. The inner case includes front and rear cover boards hingedly connected at their inner longitudinal edges to a backbone, but the inner case differs from the outer in that the same is split or divided across its width by a hinged connection disposed in spaced parallel relation to the hinged connection of the two cases, whereby the cover boards and backbone of the inner case are each divided into upper and lower sections. A binding device of a length substantially

equal to the longitudinal dimension of the binder is secured to the lower section of the backbone of the inner case, and to support the device, particularly at that portion thereof overlying the upper section of the backbone of the inner case, a metallic supporting plate is disposed between the device and the backbone of the inner case. Also, metallic reinforcing strips are secured to the outer longitudinal edges of the lower sections of the cover boards of the inner case.

10 As thus constructed, the two cases are adapted to be disposed immediately adjacent one another and folded closed whereby the solid boards of the outer case provide a very sturdy book having the appearance of a conventional loose leaf binder, within which the inner case and the display materials carried by the binding device are disposed and protected.

From the closed position, the front cover boards of the two cases are adapted to be folded away from the rear cover boards thereof, to a flat position, the conventional loose leaf binder open position, which position is ideal for the viewing of materials mounted on the binding device by two or three persons seated side by side or by a group of persons standing around a table.

From the flat viewing position, a second viewing position is obtained by moving the lower sections of the inner case toward the top edge of the outer case whereby hinged movement occurs between the top edge of the outer case and the top edge of the upper sections of the inner case and between the lower edge of the upper sections of the inner case and the upper edge of the lower sections of the inner case to dispose the upper sections of the inner case in a position approximately transverse to the plane of the outer case, whereby the lower sections of the inner case are disposed at a relatively low angle of inclination with respect to the outer case. By placing the outer case on a horizontal surface, a desk or table top, the relatively low angle of inclination of the lower sections of the inner case to the horizontal provides an optimum viewing angle for one or more people seated at the desk or table. In this position, as will be appreciated, the material to be presented is supported by the binding device and the lower sections of the inner case, the metal reinforcing plate beneath the binding device supports the portion of the binding device extending freely beyond the upper edge of the lower section of the backbone of the inner case, and the reinforcing strip at the outer edge of the lower section of each cover of the inner case rigidifies the cover sections for the firm support of the material to be presented.

50 A third viewing position is obtained by opening the binder to the flat viewing position described above, swinging the lower edges of the inner and outer case away from each other about the hinge connection at the top of the two cases, and resting the binder on the lower edges of the two cases, whereby the inner case is disposed at a relatively high angle to the surface, such as a desk or table top, upon which the binder is rested, which viewing position is highly advantageous for presentation of materials to a relatively large group of people sitting or standing at some distance from the desk or table.

60 In all of the viewing positions above enumerated, the material to be presented is mounted on the binding device and may be moved either from the rear cover to the front cover or vice versa. Also, the display sheets in the binder may bear presentation material on either 65 or both sides thereof. One particularly advantageous feature of the binder of the present invention is that the same lends itself to a simultaneous showing of pictorial representations and explanatory reading matter. For example, a picture or chart could be mounted to the rear side of one sheet and explanatory notes could be printed on the front side of the next succeeding sheet, so that

as the pages were turned, a picture or chart would be disposed at the left side of the binder and correlated printed matter would be disposed at the right. In all uses, the continuity of the material presented is excellent.

From the foregoing, it will be appreciated that the present invention provides a great many advantages in display binders, including the provision of optimum display angles for a variety of purposes, good appearance, strength and economy.

Another object of the invention is the provision of an improved display binder as above defined including means for retaining the binder in the low and high angle viewing positions described. In particular, it is an object first to provide abutment means on the inner side of the backbone of the outer case spaced from the bottom edge thereof and adapted to be engaged by the lower edge of the inner backbone to retain the binder in its low angle viewing position. Secondly, it is an object to provide strap means or the like between corresponding covers of the two cases to define and retain the binder in the high angle viewing position.

Still another object of the invention is the provision of an improved display binder including economically and practically disposed covering material for the binder, which material provides the hinged connections above described.

Other objects and advantages of the present invention will become apparent in the following detailed description of a preferred embodiment of the invention.

Now, in order to acquaint those skilled in the art with the manner of making and using the display binder of my invention, I shall describe, in connection with the accompanying drawings, a preferred embodiment of the invention and preferred manners of making and using the same.

In the drawings:

Figure 1 is a perspective view of the display binder of the invention in its closed position;

Figure 2 is a layout view of the two cases of the display binder, showing the outer side of the outer case and the inner side of the inner case;

Figure 3 is a side elevation of the binder in its high angle viewing position;

Figure 4 is a side elevation of the binder in its low angle viewing position;

Figure 5 is a cross sectional view taken along the length of the binder in its flat position, the view being taken substantially on line 5-5 of Figure 6;

Figure 6 is a cross sectional view taken along the width of the binder in its flat position, the view being taken substantially on line 6-6 of Figure 5; and

Figure 7 is a fragmentary cross sectional view taken along the length of the back bone of the binder in its low angle viewing position, showing a different form of abutment means than that shown in Figure 6.

Referring now to the drawings, I have shown the portable display binder of the present invention as including an outer case 10 made up of a full, solid or one piece, generally rectangular, front cover board 12, an identical rear cover board 14, and a full solid backbone 16 disposed intermediate the front and rear covers 12 and 14. The front and rear covers 12 and 14 are pivotally or hingedly connected at their inner longitudinal edges to the backbone 16, as is indicated at 18. The outer case, which is shown with its outer surface exposed and upside down in Figure 2, is adapted for the reception of an inner case 20, which is shown with its inner surface exposed and right side up in Figure 2. The inner case 20 is of a construction similar to that of the outer case and is made up of a front cover 22, a rear cover 24 and a backbone 26 to which the covers 22 and 24 are hingedly or pivotally connected at their inner longitudinal edges, as is indicated at 28. The outer and inner cases 10 and 20 are secured to one another by means of a hinged or

pivotal connection 30 at the top edges thereof, whereby the outer case overlies the inner, and is adapted to enclose the inner case as is shown in Figure 1.

The inner case 20 differs from the outer case 10 in that the same is divided across its width by a hinged or pivotal connection 32 disposed in spaced parallel relation to the hinged or pivot connection 30 of the two cases. As will be appreciated, the hinge connection 32 divides the components of the inner case into upper and lower sections, namely, upper and lower front cover sections 22U and 22L, respectively, upper and lower rear cover sections 24U and 24L, respectively, and upper and lower backbone sections 26U and 26L, respectively. The location of the dividing hinge or pivot 32 may be varied as desired, but preferably is so disposed that the lower sections of the inner case comprise a greater portion of the longitudinal dimension or length of the binder than the upper sections.

In manufacture, the cover sections 12, 14, 16, 22U, 22L, 24U, 24L, 26U and 26L preferably are separate boards, which may suitably comprise high grade cardboard, or the like, and the hinged or pivotal connections 18, 28, 30 and 32 are provided by an ornamental covering for the boards, as is shown in Figures 5 and 6. In particular, the ornamental covering, which may comprise leather, imitation leather, plastic and like flexible materials, includes an outer cover 34 disposed to the exterior of the outer case 10, and covering the entire exterior surface of the sections 12, 14 and 16 of the outer case and providing the hinged connections 18. At the two sides and bottom of the case, the cover 34 is folded over the edges of the outer case and suitably secured to the inner surface thereof as by gluing. At its upper edge, however, the cover 34 extends beyond the upper edge of the outer case and is secured, suitably by gluing, to the inner surface of the inner case, as is indicated at 36, whereby the cover 34 also provides the hinge connection 30. The inside or exposed surface of the inner case 20 is covered by a covering sheet 38 which overlies the portion 36 of the cover 34 and extends over the whole inside surface of the case 20 to provide the hinged connections 28 and 32, the edges of the sheet 38 being turned over the side and bottom edges of the inner case and suitably secured to the opposite surface of the case. The said opposite surface of the inner case is preferably covered by a sheet 40 which at its upper edge extends beyond the inner case and is secured to the inside surface of the outer case, whereby the same reinforces the hinge connection 30 as well as the connections 28 and 32. The inner surface of the outer case may be covered by a suitable sheet 42. In manufacture, the outer cover 34 is preferably a high-grade, wear-resistant simulated leather, the inside covering 38 is preferably a simulated, high-grade, fine-textured leather, and the sheets 40 and 42 may be of the same or cheaper grades of simulated leather.

When the boards are thus covered, a binder or binding device 44, preferably a ring binder of conventional and well known construction is secured to the lower section 26L of the backbone 26 of the inner case 20 in a conventional manner. The binder mechanism is of a length corresponding to that of the binder, but is secured only to the lower section of the inner backbone and has no connection to the backbone of the outer case nor to the upper section of the backbone of the inner case. To provide a firm support for the binder mechanism, despite its relatively limited mounting, a metal reinforcing or supporting plate 46 is secured to the lower surface of the binder mechanism 44, suitably by rivets or the like, so that the plate 46 is confined between the mechanism 44 and the backbone 26 of the inner case.

In use, the inner and outer cases are adapted to be folded, from the position shown in Figure 2, along the hinged connection 30, to dispose the inner case within the outer. The covers may then be folded simultane-

dously along the hinged or pivot connections 18 and 28 to the closed position shown in Figure 1, wherein the solid cover boards and backbone of the outer case provide a sturdy construction and afford an attractive appearance, wherein display materials detachably held in the inner case by the ring binder 44 are covered and protected and wherein the overall appearance is that, generally, of a conventional loose leaf note book. In this position, the display binder is readily transported from place to place by the salesman or other person who is to make a display presentation.

From the closed position of Figure 1, the binder is adapted to be opened to a first viewing position by moving the front covers 12 and 22 away from the rear covers 14 and 24 along the fold lines or hinges 18 and 28. When thus opened, the binder affords a flat viewing position as is shown in Figure 6 which is the normal open position of a conventional loose leaf note book. The flat viewing position is ideal when the materials in the book are to be viewed by one, two or three people sitting side by side, with one of the people holding the binder, and when the materials are to be viewed by a group of people standing around a table upon which the binder is laid.

A second viewing position is obtained by disposing the binder in the flat viewing position and moving the lower edge of the inner case toward the top edge of the cases, or in other words, with the binder in the flat position facing a viewer, the top ring of the binder mechanism 44 may be grasped and moved away from the viewer. Such movement results in relative pivotal movement between the upper and lower sections of the inner case, about the hinge 32, and between the upper sections of the inner case and the outer case about the hinge 30, whereby the upper sections 22U, 24U, and 26U, of the inner case are moved to a position generally transverse of the outer case 10 and the lower sections 22L, 24L, and 26L, of the inner case are moved to a relatively low angle of inclination with respect to the outer case, as is shown in Figure 4. To support and retain the binder in this low angle viewing position, suitable abutment means is secured to the backbone of the outer case in spaced relation to the lower edge thereof, which means is adapted to be engaged by the lower edge of the backbone of the inner case, whereby the inner case is held as is shown in Figure 4. While the abutment means is preferably secured to the backbone of the outer case, it will be appreciated that the means may, if desired, be provided on either or both of the cover boards as well. The abutment means may take various forms, for example, the form of a button 48, as shown in Figures 4 and 6, extending through the outer backbone 16 and projecting above the inner surface of the same for engagement by the lower edge of the inner backbone 26. As an alternative, a metallic strap or strip 50, as shown in Figure 7, may be secured to the outer backbone 16, suitably by rivets 52, the strip including an upstanding end portion 54 adapted to be engaged by the lower edge of the inner backbone 26. The button 48 is preferably headed, and the end portion 54 of the strip 50 is preferably spaced from the inner surface of the backbone 16 by a suitable distance, so that the lower edge of the backbone engages under the abutment means to provide a positive positioning and retaining means. However, the abutment means does not project sufficiently above the inner surface of the outer case in any way to obstruct the disposition of the inner case within the outer case in the flat or closed position of the binder, as will be appreciated from Figures 1 and 6.

The angle of inclination in the low angle viewing position may be varied to meet particular requirements, but I have found the 25 degree position to be optimum. Accordingly, the length of the upper and lower sections of the inner case and the disposition of the abutment means are preferably such as to provide a viewing angle

of approximately 25 degrees. For example, in a binder having an overall length of 12", the inner case may suitably be approximately 11½" in length, the lower edges of the inner and outer cases being spaced by ½", and may suitably be divided into upper sections of 3½" in length and lower sections of 8¾" in length, in which case the abutment means could suitably be disposed approximately 3¾" from the lower edge of the outer case to provide a 22 degree angle of disposition of the lower sections of the inner case with respect to the outer case, which angle is sufficiently close to 25 degrees for present purposes.

The low angle position affords an optimum viewing surface for the presentation of display materials to one or more persons seated at a desk or table. In such position, the material to be displayed is detachably retained by the ring mechanism 44, and is supported on the lower sections 22L, 24L, 26L, of the inner case 20 and by the end portion of the ring mechanism 44 extending freely beyond the hinged connection 32. The reinforcing or supporting plate 46 serves to rigidify and support this portion of the ring mechanism, whereby the display material is adequately and firmly supported and whereby the ring mechanism is retained stationary while sheets of display material are moved from one cover to the other. All sections of the cases 10 and 20 are preferably formed of substantially rigid material, as will be appreciated from the foregoing, so that the assumption of the different viewing angles by the binder is readily and conveniently accomplished, and in all positions, a firm support and retention of the display material is provided. However, it is to be noted that the supporting plate 46 rigidifies and supports the lower section 26 of the inner backbone and engages the abutment means, 48 or 50, whereby the inner backbone 26 may be made of relatively light stock. To rigidify and support the remainder of the inner case, and to accommodate the utilization of relatively light stock in the formation of all of the sections of the inner case, the lower sections 22L and 24L of the front and rear covers 22 and 24, respectively, of the inner case are preferably reinforced by channel or U-shaped metallic members 56 engaged with the outer longitudinal edges of those sections. Preferably, the reinforcing members 56 are applied to the sections 22L and 24L prior to assembly and covering of the sections so that the same are hidden from view and thus do not detract from the esthetic appearance of the binder.

A third viewing position is afforded by the display binder of the present invention by opening the binder to its flat position, swinging the lower edges of the two cases apart about the hinged connection 30, and resting the binder on the lower edges of the two cases, as is shown in Figure 3, thus to provide a high angle viewing position. In such position, the upper and lower sections of the inner case tend to pivot with respect to one another in a direction opposite to that occurring in the low angle viewing position, so that the inner case, due to the disposition of the binding mechanism 44, effectively comprises solid cover boards and a solid backbone whereby the high viewing angle position is maintained. While the high angle viewing position may be varied, I have found 65° to be an optimum position for substantially all types of displays. Accordingly, I provide limit or stop means between the two cases 10 and 20 to limit the spreading thereof to such position as will afford approximately a 65° inclination of the inner case to the surface upon which the binder is rested. Preferably, such limit or stop means is in the form of a flexible, but non-stretchable, strap 58 or the like suitably secured to the inside of the outer case 10 and the outer side of the inner case 20, suitably by means of rivets 60 or the like. When the abutment means, 48 or 50, is provided on the backbone, as is preferred, straps 50 are preferably disposed between both the front covers 12 and 22 and the rear covers 14 and 24 of the two cases, the straps prefer-

ably being secured to the lower sections of the covers of the inner case as is indicated by the disposition of the rivets 60 in Figure 2. However, other placement of the strap or straps may be employed as desired. As an example of the disposition of the straps 58, reference is made to the binder described in the above discussion of the low angle viewing position, which binder has an outer case 12" in length and an inner case 11½" in length. In such binder, a spacing between the lower edges of the two cases of 6¾" will afford the 65 degree viewing angle desired. To provide a limit or stop at this angle, the straps 58 may suitably be of a length to provide a span between the two cases of 3¾" and be secured to the inner case at 5" from the lower edge thereof and to the outer case at 5½" from the lower edge thereof. To provide an attractive external appearance, the rivets 60 secured to the outer case are preferably applied to the cover boards 12 and 14 prior to application of the outer covering 34, as is indicated in dotted lines in Figure 2. As will be appreciated, the high angle viewing position is ideal for the presentation of display materials to a group of persons sitting or standing at some distance from a table or desk upon which the binder is rested in the position described.

In some instances, it may be desirable to dispose the display binder at an elevation higher than that of a table or the like, such as when a person is making a presentation to a large group of people while standing before them, in which case, the hinge connection 30 accommodates support of the binder in its flat position, but vertically disposed, by passing a supporting string between the two cases 10 and 20 and resting the material defining the hinge 30 on such string.

In all viewing positions provided, the display sheets to be shown are mounted on the ring mechanism 44 and may be freely moved from one side of the binder to the other to provide a consistent continuity of display materials. The display sheets may bear display matter on either or both sides thereof, and the disposition of the sheets in side by side relation, after at least one sheet has been turned, particularly accommodates the simultaneous presentation of pictorial and written displays, as has been pointed out hereinbefore. The ring binding mechanism accommodates the ready assembly and mounting of display materials and provides a very convenient apparatus for revising and changing the sequence of the display sheets.

From the foregoing, it will be appreciated that the present invention provides an improved display binder that is highly economical and practical in manufacture and assembly, that is very sturdy and attractive, and yet light in weight, that provides three viewing angles, each of which is optimum for certain conditions, with the three positions meeting all conditions, and that assures perfect continuity of the materials displayed.

While I have described what I regard to be the preferred embodiment of my invention, it will be appreciated that various changes, rearrangements and modifications may be made therein without departing from the scope of the invention, as defined by the appended claims.

I claim:

1. A display binder comprising similar outer and inner cases, said outer case including a pair of substantially rigid covers hingedly connected with respect to each other along the inner edges thereof, said inner case including a pair of covers hingedly connected with respect to each other along the inner edges thereof and each including substantially rigid corresponding sections hingedly connected along a common line transversely of the hinged connections of said covers, said cases being hingedly connected to one another along one edge thereof transversely of the hinged connections of said covers and in spaced parallel relation to the hinged connection of the sections of each cover of said inner case, a binding device carried by said inner case, said device being secured to said inner

case adjacent and parallel to the hinged connection of said covers of said inner case and only to the side of the hinged connection of the sections of said covers of said inner case opposite the hinged connection of said cases, the binder affording a flat viewing position by moving the two sets of corresponding covers of the two cases away from one another about the hinged connections of said covers, a low angle viewing position by disposing the binder in said flat position and moving the edge of said inner case opposite the hinged connection of said cases toward the hinged connection of said cases to dispose the sections of each cover of said inner case at an inclination to the covers of said outer case, and a high angle viewing position by disposing the binder in said flat position, moving the edges of said cases opposite the hinged connection thereof apart and resting the binder on the said edges of said cases, stop means between corresponding portions of said cases limiting separation of said cases to define the high angle viewing position, and abutment means mounted adjacent the edge of said outer case opposite the hinged connection of said cases and engageable by the adjacent edge of said inner case to define the low angle viewing position.

2. A display binder comprising generally similar inner and outer cases, each comprising a backbone and front and rear covers hingedly connected at their inner longitudinal edges to the backbone, said cases being hingedly connected to one another along one edge thereof transversely of the connections of said covers, said backbone and covers of said inner case each comprising corresponding sections hingedly connected along a common line in spaced parallel relation to the hinged connection of said cases, a binding device of a length substantially equal to the longitudinal dimension of said inner case connected to the section of the backbone of said inner case opposite the hinged connection of said cases, the binder affording a flat viewing position by folding the corresponding sets of covers of the two cases away from one another to dispose the backbone and the two covers of each case in substantially the same plane, a low angle viewing position by disposing the binder in the flat position and moving the edge of the inner case opposite the hinged connection of the two cases toward said hinged connection to dispose the sections of each member of the inner case at an inclination to the corresponding members of the outer case, and a high angle viewing position by disposing the binder in the flat position, spreading the lower edges of the two cases apart and resting the binder on the lower edges of the two cases, stop means between corresponding portions of the two cases limiting separation of the cases to define the high angle viewing position, said stop means and said cases being so related as to dispose said inner case at an angle of approximately 65° to the surface upon which the binder is rested, and abutment means secured to said outer case and projecting toward said inner case, said abutment means being engageable by the edge of said inner case opposite the hinged connection of said cases to define the low angle viewing position, said abutment means and the dimensions of said outer case and the sections of said inner case being so related as to dispose the section of the backbone of said inner case to which said binding device is connected at an angle of approximately 25° with respect to the plane of said outer case.

3. A display binder comprising an outer case and an inner case, said outer case including a solid backbone and solid front and rear cover boards hingedly connected to said backbone at their inner longitudinal edges, said inner case comprising a backbone and front and rear cover boards hingedly connected to said backbone at their inner longitudinal edges and each comprising corresponding upper and lower sections hingedly connected along a common line, said cases being hingedly connected along the top edges thereof in spaced parallel relation to the hinged connection of the upper and lower sections of said

backbone and covers of said inner case, the hinged connection of the upper and lower sections of said inner case being disposed nearer the top edge of said inner case than the lower edge thereof, a binding device of a length substantially equal to that of the backbone of said inner case secured solely to the lower section of the backbone of said inner case, a supporting plate disposed between the backbone of said inner case and said binding device to support the portion of said binding device adjacent the upper section of the backbone of said inner case, the binder affording a flat viewing position by moving the front covers away from the rear covers to expose said binding device, the binder affording a low angle viewing position by disposing the same in said flat position and moving the lower edge of said inner case toward the top edge of said outer case to dispose the upper sections of said inner case generally transversely of the outer case, the binder affording a high angle viewing position by disposing the same in said flat position, moving the lower edges of said cases away from one another and resting the binder on the lower edges of said cases, abutment means mounted on the backbone of said outer case between said cases in spaced relation to the lower edge of said cases, said abutment means being adapted for engagement by the lower edge of the backbone of said inner case to retain the binder in said low angle viewing position, the length of the sections of said inner case and the disposition of said abutment means being such as to provide a low viewing angle of approximately 25°, reinforcing strips applied to the outer longitudinal edges of the lower sections of said covers of said inner case, and stop means extending between and connected to at least one cover of said outer case and the lower section of the corresponding cover of the inner case to retain the binder in said high angle viewing position, said stop means defining a maximum separation between said cases

to dispose said inner case at a high viewing angle of approximately 65°.

4. A loose-leaf binder for containing and for displaying contained material comprising an inner cover member including front, back and intermediate portions, an outer cover member coextensive with said inner cover member when said binder is closed including front, back and intermediate portions, said inner and outer cover members being pivotally connected along the upper edges 5 permitting said members to separate at the lower edges and form an easel, flexible strap members secured at their ends to and limiting separation of said members, a hinge-break transversely across said inner cover member below the upper edge and above the transverse center line permitting the portions therebetween to pivot rearwardly and downwardly, means secured to said outer cover member engageable by the lower edge of said inner cover member when the portions of said inner cover member above said hinge-break are in rearwardly and downwardly folded 15 position providing a second easel, and a ring metal secured to the intermediate portion of said inner cover member for retaining material to be contained and displayed, said ring metal being free of said intermediate portion of said inner cover member above said hinge-break.
